OF FLUSHING, NEW YORK

WINDING MECHANISM FOR ROLLING SCREENS

Application filed December 2, 1925. Serial No. 72,780.

This invention relates to rolling screens or shades, and more particularly refers to a novel and improved arrangement for winding and unwinding a rolling screen or shade, whereby certain important advantages may be realized, which similar devices heretofore in use fail to afford.

The primary object of this invention, is to provide an improved arrangement whereby 10 a rolling screen or shade will be subjected to an even tension, which will remain practically uniform while the screen is extended from its inoperative to its operative position.

Another object of this invention is to provide a novel and improved arrangement of rolling screen or shade, whereby a positive winding action will be obtainable at all 20 times, while at the same time the tension upon the winding element is maintained, insuring close and smooth winding; preventing, as a consequence, the possibility of distortions and kinking of the material.

A still further object is to provide, in a rolling screen or shade, an extremely simple and reliable arrangement, whereby perfect alignment of the winding member is assured at all 25 times, and ease of control and effective operation are obtained.

Rolling screens are generally made of very fine mesh wire netting, produced from light gauge metallic wire, which is a fairly flexible and pliable fabric, which can be wound upon and unwound from a roller with comparative ease. This fabric, however, is not quite as flexible as cloth, and the material has a certain springiness which makes it rather difficult to wind it closely upon the roller, unless some special arrangement is resorted 30 to. Arrangements to insure close winding are generally lacking in devices of this character, and the result is that when a screen is wound up, its various coils are detached from each other, and the fabric is likely to become 35 distorted and irregular when tension is applied for unwinding.

After a certain period of use, a screen thus subjected to the resulting strains loses its uniformity, its surface becomes kinked at numerous points, and the grain of the metal

rapidly crystallizes, becoming brittle and hard.

As a general rule, these screens are mounted upon rollers depending on a spring for the winding action, after the fashion of the ordinary roller for window shades.

The screen may be unwound from the roller by pulling at its free end to extend the screen, against the action of a coil spring tending to rotate the roller in the opposite direction. A pawl and ratchet mechanism, or some other similar device, is employed to prevent return motion of the roller, or else the screen itself may be locked against obeying the action of the spring, the two edges of the screen running within side rails acting as guiding means therefor.

When the screen is released, or the spring is otherwise permitted to rewind the roller, the screen may be restrained to a certain extent, slowing up the winding action, to prevent its winding too loosely upon the roller, but this restraining action cannot be exerted beyond a certain limit, inasmuch as a tension such as would be required to maintain the fabric close to the surface of the roller would generally be sufficient to altogether prevent the action of the spring, owing to the imperfect flexibility of the fabric. Furthermore, the exertion of such a restraining 75 action, requires the exercise of judgment and a certain degree of experience, which are not often at the command of an untrained woman or child.

Close winding is therefore virtually impossible under these conditions, with the objectionable results previously pointed out. Another objectionable consequence is, that sufficient room must be left within the casing 80 surrounding the roller, to allow loose winding of the fabric. The appearance of the device is all important, and the necessity of having a bulky casing for the roller is a distinct disadvantage; and in order to maintain said 85 casing or top rail within a reasonable size, another unsatisfactory condition is introduced, by the use of a roller of insufficient diameter, compelling the fabric to be wound and bent on a radius which is too small for 90 100

its texture, and which further assists its tendency to crystallization.

This method of construction is furthermore open to one more serious objection. It is obvious that if the screen is to be entirely rewound upon the roller, the spring actuating the roller must still be under sufficient tension to cause winding action at the time when the operation is about to be completed; this is equivalent to saying that the tension of the spring increases more and more as the screen is extended, owing to the construction of the device, so that this tension is likely to become excessive when the screen is entirely unwound. This means both that an excessive force must be applied in order to operate the screen, and that the screen becomes subjected to an excessive tension when in its extended position; this tension may cause undue stretching of the fabric, which may, in the long run, produce harmful consequences, by destroying the uniformity of its weaving.

The arrangement forming the object of the present invention insures almost uniform and moderate tension at all times, positive control, and close winding of the screen upon the roller; no waste space need therefore be provided for undue expansion of the diameter of the roller, and the roller itself need therefore not be made of an excessively small diameter for the sake of appearance. At the same time the mechanism adopted is very simple and reliable, and its cost of production compares favorably with that of other similar devices heretofore in use.

An embodiment of my invention is shown in the drawings, in which:

Fig. 1 is a fragmentary front view in elevation partly sectioned of a self adjustable rolling screen where the arrangement forming the object of the present invention is illustrated;

Fig. 2 is a similar view showing also the bottom rail and the operating mechanism, illustrating the application of the device to a narrower window frame.

The present invention is an improvement over the device which has been described and claimed by me in two other patent applications filed simultaneously herewith, having for title "Adjustable rolling screen" Serial No. 72,761, patented October 21, 1930, Patent No. 1,779,262, and "Clamping mechanism for rolling screens", Serial No. 72,762, patented March 25, 1930, Patent No. 1,751,950, the improvement being more particularly directed to the winding mechanism for the rolling screen which has been considerably simplified in the present case and which has been made more reliable in its operation.

The two patent applications above referred to relate, respectively, to an adjustable construction of rolling screen frame and roller and to a novel and improved clamping mechanism for clamping the side edges of the

screen when in operative position. These two features have been embodied in the present invention, practically unchanged and have been represented in the drawings in order to be described for the sake of clarity; but the invention, as stated, refers more particularly to the arrangement for winding and unwinding the screen.

My device consists, essentially, of a screen or shade 10, made of suitable fabric, attached at one end, in this case the upper end, to a roller 11, rotatably mounted within a casing or upper rail 12, and provided at the other end with a cross member or bottom rail 13, extending for the entire width of the screen, by means of which the screen may be operated in one or the other direction.

The bottom rail has the object of uniformly distributing the force applied to extend the screen; means are also provided to insure correct alignment of the bottom rail at all times, to prevent uneven stretching of the screen, causing said bottom rail to occupy successive parallel positions throughout its travel from one end of the screen frame to the other.

In the present case, these means are represented by side belts 14, 15, which are attached to and wound upon upper pulleys 16, 17 and which run over lower pulleys 18, 19 respectively, each belt being attached to one end of the bottom rail. The arrangement is such that the movement of the belts is interdependent because the upper pulleys are fixed on the same shaft 20, on which the roller 11 is also rotatably mounted; therefore, the bottom rail can only move by simultaneous displacement of its ends, and of the belts connected thereto, by equal quantities, corresponding to equal angular movements of the pulleys.

Proper alignments of the bottom rail and uniform movements of the screen throughout its width, are in any event assured, owing to the fact that the arrangement causes the screen to become closely wound upon the roller, so that any movement of the screen is instantly transmitted to the roller and through the roller to the entire width of the screen.

As stated, the roller is rotatably supported upon shaft 20, having its ends inserted within hollow studs 21, 21', one at each end, said studs being riveted or otherwise secured on to side frame members or side rails 22, 23, which are placed and secured against the inside surface of the window frame 24', by means of screws or in some other suitable manner in a vertical position. The studs project inwardly and co-axially to each other in a horizontal direction and are formed with a hollow stem portion which acts as a bearing for said shaft 20. Pulleys 16, 17 are fixed upon shaft 20 by means of set screws 24, so that the said pulleys may be set on the shaft at whatever distance it may be required to fit

the screen frame within window frames of slightly different widths.

Stock windows of the same size are, of course, not exactly alike and there may be a difference of $\frac{1}{4}$ " to $\frac{3}{8}$ " in width between under-sized and over-sized windows; studs 21, 21' and shaft 20, are made so that when the screen frame is mounted in a window frame of a width smaller than normal by say, $\frac{1}{4}$ ", the ends of the shaft almost touch the bottom of the openings in the studs; and when the screen frame is mounted in an over-sized window frame, the width of which is, say $\frac{1}{4}$ " in excess of normal, the distance between the two studs is still less than the length of the shaft and sufficient bearing surface is still provided by said studs for said shaft. Pulleys 16, 17, can therefore be set in position on the shaft by means of set screws 24 so as to cause said shaft to remain centrally located between said studs.

The lower pulleys 18, 19 are rotatably mounted upon said stud rivets such as 28, riveted to the side rails, so as to remain in the same plane, with the upper pulleys; however, owing to the fact that the upper pulleys are of a larger diameter than the lower pulleys, the center of rotation of the upper pulleys is forwardly displaced in relation to the center of the lower pulleys; so that the inner strand of each belt to which the bottom rail is attached, is substantially in line with the rear and the circumference of the screen roller when such roller is at its maximum diameter, the screen moving up or down as close as possible to the window sashes. Accordingly, the belts are guided from the upper pulleys to and into the said rails by suitable deflecting means, not shown.

In relation to the bottom rail the screen and the belts form a continuation; but said screens and belts are so arranged in relation to the screen roller and to the upper pulleys that when the screen is unwound from the roller, the belts will be wound upon the pulleys; and vice versa. As the screen and belts are thus wound and unwound, the diameter of the roller and the pulleys vary and I take advantage of this circumstance in creating a tension upon the screen at all times which, although sufficient for the purpose of keeping the screen taut is never excessive, varying between two limits which are not far apart.

The arrangement illustrated, as stated, is preferably made adjustable for slight variations which may occur in the width and length of window frames of the same stock size and therefore, pulleys 16, 17 may be set upon the shaft 20 for different distances between the side rails. It is also necessary, however, to set the screen roller centrally of the frame at all times, and this may be automatically obtained in a manner similar to the one described in my other patent appli-

cation entitled "Adjustable rolling screen". By referring to the drawings it is seen that collars 25, 26 are attached to the roller at the same distance from each end thereof. The roller is mounted centrally upon shaft 20 by causing the hub of disc 30 and a collar 31, fixed on shaft 20 to abut inversely against said collars 25, 26 so that an axial movement of the roller in relation to the shaft is prevented. Between said collars 25, 26 and wheel 16, 17 respectively may be interposed pressure springs 32, 33, which are of the same size and which by pressing against said pulleys and collars will cause the shaft to automatically assume a central position in relation to its bearings when set screws 24, are loosened. Once the frame and roller are mounted in position, set screws 24 may be once more made operative to fix the shaft and the shaft will remain permanently set in its proper place. However, the differences between widths of windows of the same stock size are so small that the proper position of the roller and shaft may be gauged without the assistance of the springs so that springs 32, 33 may be omitted if desired.

On the other hand, if springs 32, 33 are used, pulleys 16, 17 may be mounted upon the shaft so as to be axially movable on said shaft but constrained, to rotate therewith, for instance, by means of key connection 32', 33', shown in dotted lines in Fig. 2; and in this case, the use of the set screws may be omitted, the pulleys being held in their proper position by the pressure exerted by springs 32, 33.

In addition to the adjustable roller, the device also implies as a natural consequence, the use of an adjustable bottom rail; and for the sake of illustration this is merely represented as being composed of a central member or bottom rail proper 13 and two end members 70, 71, attached to side belts 14, 15, respectively, telescoping within said bottom rail, that is, in the sense of the width of the screen. By means of this construction, the force actuating the bottom rail to move the screen up or down is transmitted to the screen or to the side belts and the length of the bottom rail at all times adjusts itself, automatically to the distance between the belts.

It will be observed that the arrangement described is very flexible and effective, inasmuch as it will operate equally well if the side rails do not run in absolutely parallel directions. This is an important advantage because, owing to the quantity production methods, used in their manufacture, window frames are rarely of the same exact dimensions and the width or height or both of the same frame may vary at different points.

These possible variations of the dimensions of the window frame, imply the necessity of using an adjustable frame for the screen; in other words, the feature of adjustability must

extend first to the screen frame, which must be capable of adapting itself, within limits, to these variations, and then to the roller and screen, which must be adjustable, possibly automatically, to the dimensions thus acquired by the screen frame. At the same time, it is highly desirable that a neat outside appearance of the device be preserved.

1. In connection with the winding mechanism 10 to which the present invention more particularly refers, I prefer to also use a mechanism for clamping the side edges of the screen when extended in its operative position, in order to insure tight closing at the edges of 15 the window to which the screen is applied, at the same time preventing possible bulging or distortion of the screen, due to window pressure or to other causes.

The side rails are in the form of a longitudinal casing of a section suitable to receive and conceal the belts and pulleys, and such other parts of the mechanism as the device may include; for instance, clamping means for the edges of the screen, such as described 25 in an application for patent entitled "Rolling screens", filed by me February 13, 1923, Serial No. 618,762, patented July 7, 1925, Patent No. 1,656,282 or such as described in another application for patent on "clamping mechanism 30 for rolling screens", filed simultaneously herewith.

The drawings are mainly intended for the purpose of illustration, and not in a limiting sense; since it is obvious that minor changes 35 may be made in the construction of the device, without substantially departing from the inventive idea. Therefore, I reserve myself the right to carry my invention into practice in all those ways and manners which may enter, 40 fairly, into the scope of the appended claims.

I claim:

1. In a device of the class described, comprising two side frame members, a shaft rotatably mounted between said members, a 45 roller rotatably mounted upon said shaft, a screen adapted to be wound upon said roller, two side pulleys carried by said shaft, flexible elements attached at one end to the free end of said screen and at the other end to said pulleys, and a spring inserted within said roller connecting said roller to said shaft, causing said flexible member to be wound upon said pulleys as said screen is unwound from said roller, means for adjusting the position of said pulleys along and for fixing the same upon said shaft so as to position said shaft between said two side members, preventing axial displacement of said shaft in relation thereto, and means for 55 preventing axial displacements of said roller in relation to said shaft.
2. In a device of the class described, comprising two side frame members, a shaft rotatably mounted between said members, a 60 roller rotatably mounted upon said shaft, a

screen adapted to be wound upon said roller, two side pulleys fixed upon said shaft restraining the same against axial movements in relation to said side members, flexible elements attached at one end to the free end 70 of said screen and at the other end to said pulleys and a spring inserted within said roller connecting said roller to said shaft, causing said flexible members to be wound upon said pulleys as said screen is unwound 75 from said roller, and means interposed between said pulleys and said roller for centering said roller upon said shaft in relation to said side pulleys.

3. In a device of the class described, comprising two side frame members, a shaft rotatably mounted between said members, a roller rotatably mounted upon said shaft, a screen adapted to be wound upon said roller, two side pulleys fixed upon said shaft restraining the same against axial movements in relation to said side members, flexible elements attached at one end to the free end of 80 said screen and at the other end to said pulleys and a spring inserted within said roller 85 connecting said roller to said shaft, causing said flexible members to be wound upon said pulleys as said screen is unwound from said roller, and means interposed between said pulleys and said roller for automatically centering said roller upon said shaft in relation to said side pulleys. 90

4. In a device of the class described, comprising two side frame members, a shaft rotatably mounted between said members, a roller rotatably mounted upon said shaft, a screen adapted to be wound upon said roller, two side pulleys loosely carried by and longitudinally adjustable on said shaft, flexible elements attached at one end to the free end 100 of said screen and at the other end to said pulleys, and a spring inserted within said roller connecting said roller to said shaft, causing said flexible member to be wound upon said pulleys as said screen is unwound from said roller, means for fixing the pulleys upon said shaft so as to position said shaft between said two side members, and a spring inserted between each pulley and said roller automatically centering said roller in relation to said pulleys when the pulleys are loose on the shaft. 110
